FIG. 1 is a side elevational view of my design for a hand-held extruder;

FIG. 2 is a front elevational view of the hand-held extruder of my design; and

FIG. 3 is a plan view of the hand-held extruder embodying my new design.

The characteristic features of my design reside in a hand-held extruder having a streamlined, raked silhouette and a decorative and functional rib pattern on the handle.

I claim:

The ornamental design for a hand-held extruder, substantially as shown and described.
